Inventor
Alexander Clapperton,
By his Attorney

P. Wooster.

UNITED STATES PATENT OFFICE.

ALEXANDER CLAPPERTON, OF YONKERS, NEW YORK.

PILE-CUTTER.

1,381,905.

Specification of Letters Patent. Patented June 21, 1921.

Application filed May 27, 1920. Serial No. 384,538.

To all whom it may concern:

Be it known that I, ALEXANDER CLAPPERTON, a citizen of the United States, and resident of Yonkers, in the county of West Chester and State of New York, have invented certain new and useful Improvements in Pile-Cutters, of which the following is a specification.

This invention relates to a pile cutting mechanism for looms, wherein a cutting tool traveling along a wire woven in the fabric, severs threads to form the pile of the fabric.

This invention relates to the class of pile cutters wherein the knife is separate from the wire, as distinguished from those in which the wire carries a knife at one end, or wherein a knife travels in a channelled wire. In the latter, a U-shaped wire is usually employed, with a vertically disposed knife traveling in the groove, which is objectionable owing to the special form of wire required, the frequency of sharpening required, breakage, and complexity of control.

This invention has for its object to provide a pile cutting mechanism operating in connection with round or oval wires with the cutting edge at an angle to the wire and moving in a horizontal plane, and actuated to be in cutting position during movement in one direction and out of cutting position during reverse movement. During the latter movement, the knife can be easily sharpened, so that delays for replacing knives are avoided.

With these objects in view, the invention comprises various features of construction, as hereinafter described in the following specification, and pointed out in the claims, reference being made to the appended drawings, in which—

Figure 1 is a front elevation of a loom, showing the invention assembled thereon.

Fig. 2 is a fragmentary view on line 2—2, Fig. 1, the wire and fabric tufts being enlarged for the purpose of illustration.

Fig. 3 is an enlarged side elevation of the cutting mechanism finishing its cutting stroke and being automatically shifted for the sharpening operation and return stroke.

Fig. 4 is a plan view of the cutting tool and its shifting mechanism, and

Fig. 5 is an enlarged view of the cutting mechanism on line 5—5, Fig. 3.

Referring to the drawings, 1 indicates the main frame of a loom having a take up roll

2 for the fabric 3, which is woven upon pile wires 4, and then cut to form the tufts 5, generally found in rugs or carpets. As the looms for weaving the fabric and cutting the pile are now in general use, I do not disclose details other than my improvement in the cutting mechanism, which constitutes my invention. For this purpose, I provide a knife 6, which resembles an ordinary pawl, with a horizontal cutting edge 7, parallel to the surface of the fabric and extending diagonally of the wire to have a slitting action. The knife is pivoted at 8, for example, upon a cap screw 9 having a shouldered fit at 10 where secured to the cross-head 11, which latter is slidable on the guide bar 11^a. A coil spring 12 is fastened to the knife 6 at 13 and in the screw 9 at the other end 14, for normally holding the knife 6 elevated, as shown in dotted lines, Fig. 3. A pin 15 on the knife limits the upward throw by striking stop pin 16 on the cross head 11. The knife 6 carries an actuating pin 17 engaging the slot 18 of a slide-plate 19 on cross head 11, and having a slot 20 engaging pin 21 of the cross head 11. The reciprocating movement of the slide plate is effected through the connecting rod 22, operated from a fulcrumed lever 23 pivoted at 24 to the wire carriage 25 slidable on the guide bar 25^a. A foot 28 is mounted on the knife 6 to slide on a woven in wire one or more behind the one being cut, so that the knife will not drop if one wire is missing. The knife can be held clear of its operative position, by pulling it out in slot 18 of slide plate 19 to clear pin 16, but not clearing pin 30, between which latter and the pin 16 the pin 15 is held by the torsion spring 95. In this position, the knife 6 is held clear from cutting, until it is again desired to resume the cutting operation. A pin 31 further regulates the cutting level of the edge 7, and may be arranged to be adjustable, so as to prevent the knife dropping too low when there is no wire present under the knife.

In operation as thus far described, the fabric is fed forward step by step, and synchronized therewith is the reciprocation of the knife. The raising and lowering of the knife during the return and cutting strokes respectively is accomplished as follows: Consider the knife to be nearing the end of its cutting stroke. It will be traveling toward the right, in Figs. 1 and 3, by reason

of the motion communicated through pin 21 and slot 20 to cross head 11. The pressure between pin 17 and slot 18 will also assist somewhat in urging the knife forward in its travel. The primary purpose, however, of pin 17, bearing on the left hand edge of slot 18, is to hold the knife in cutting position, against the stop pin 31, which limits the downward movement of the knife. Now 10 as the rod 22 and slide 19 reach the end of their travel, and begin their return stroke, no motion to the left can be communicated through the pin 21 to the cross head 11 until the right hand end of slot 20 comes into 15 bearing with the pin. Meanwhile the right hand edge of slot 18 is moving the pin 17 to the left, thus rotating the knife upward until the pin 17 strikes against the right hand side of stop pin 31. The right hand 20 end of slot 20 will now come into engagement with pin 21, and will move cross head 11 and knife to the left. The lowering of the knife at the beginning of the cutting stroke is accomplished in reverse manner.

25 The sharpening mechanism comprises a stationary stone 36 held in an adjustable holder 37 by clamp 38 above the knife 6, which, when the latter is resiliently lifted as described in the foregoing paragraph, 30 will be drawn over the stone 36 during the initial portion of its return stroke. The upper position of the knife is determined by the engagement of pin 17 with pin 31, and the grinding action of stone upon the knife 35 is thus controlled to maintain the bevel at the proper angle.

The wires 4 are preferably tapered to a round top edge as shown, but can be round, oval or U-shaped, and each wire has the 40 usual eye or hook at the end (according to the wire inserting and pulling means used in the loom) for inserting and pulling out. An advantage of this cutting mechanism is that the wire can be pulled out on the same 45 stroke with the cutting, as will be seen from Fig. 3.

Various modifications and changes may be made in the details of construction without

departing from the scope of the appended claims.

What I claim is:

1. A pile cutter comprising a reciprocating cross head, a knife pivoted thereon, and an actuating connection between the cross head and knife for throwing the knife into 55 and out of cutting position before each reciprocation.

2. A pile cutter comprising a cross head carrying a knife pivoted to move vertically to and from operative position, a slide on 60 the crosshead having a limited relative movement, and a connection from the slide for swinging the knife to and from operative position.

3. A pile cutter comprising a reciprocating cross head, a knife pivoted thereon to swing to and from cutting position, a slide on the cross head having limited movement, 65 actuating means connected to the slide, and a connection between the slide and knife for controlling the position of the knife. 70

4. A pile cutter comprising a reciprocating cross head, a knife pivoted thereon, a sharpening means for said knife, and an actuating connection between the cross head 75 and the knife for throwing the knife into and out of cutting position before each reciprocation, and for holding the knife in operative engagement with said sharpening means.

5. In combination with a plurality of pile wires, a pile cutter comprising a cross head adapted to reciprocate in the direction of said wires and carrying a knife pivoted to move to and from operative position, said 85 knife being in operative position when the cross head moves in one direction and out of operative position when the cross head moves in the other direction, and a foot carried by the knife and traveling on a wire 90 lateral of the pile being cut, to prevent the knife from falling below operative position.

Signed at New York, in the county of New York and State of New York, this 24th day of May, A. D. 1920.

ALEXANDER CLAPPERTON.
